(57) **CLAIM**

The ornamental design for a handbag, as shown and described.

DESCRIPTION

FIG. 1 is a front perspective view of an alternative embodiment of the handbag shown in FIG. 1;

FIG. 2 is a front view of the handbag shown in FIG. 1;

FIG. 3 is a rear view of the handbag shown in FIG. 1;

FIG. 4 is a left side view of the handbag shown in FIG. 1;

FIG. 5 is a right side view of the handbag shown in FIG. 1;

FIG. 6 is a top view of the handbag shown in FIG. 1;

FIG. 7 is a bottom view of the handbag shown in FIG. 1;

FIG. 8 is a front perspective view of another alternative embodiment of the handbag shown in FIG. 1;

FIG. 9 is a front view of the handbag shown in FIG. 8;

FIG. 10 is a rear view of the handbag shown in FIG. 8;

FIG. 11 is a left side view of the handbag shown in FIG. 8;

FIG. 12 is a right side view of the handbag shown in FIG. 8;

FIG. 13 is a top view of the handbag shown in FIG. 8; and,

FIG. 14 is a bottom view of the handbag shown in FIG. 8.

The broken line showing of portions of the body of the handbag, chain handles, handle rings, front chain and front plaque in relevant drawings shows unclaimed subject matter for the design in those drawings.

The break lines shown in the drawings of the chain handle indicate indeterminate length.
